UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

1,418,901.

Specification of Letters Patent. Patented June 6, 1922.

Application filed January 26, 1921. Serial No. 440,035.

To all whom it may concern:

Be it known that I, JOHN H. BARR, citizen of the United States, and resident of the borough of Manhattan, city of New York, 5 in the county of New York and State of New York, have invented certain new and useful Improvements in Typewriting Machines, of which the following is a specification.

10 My present invention relates to line spacing mechanism for typewriting machines and its principal object is to provide new and improved mechanism of the character specified.

15 To the above and other ends which will hereinafter appear, my present invention consists in the features of construction, combinations of devices and arrangements of parts to be hereinafter described and particularly pointed out in the claims.

20 In the accompanying drawings which illustrate the preferred form of my invention,

Figure 1 is a fragmentary vertical sectional view taken transversely of the platen carriage near its right-hand end and outside the platen, the platen ratchet wheel being indicated by dotted lines.

25 Figure 2 is a fragmentary vertical sectional view corresponding to Fig. 1 but omitting some of the parts shown in said Fig. 1 and showing other parts in different relationships.

30 Figure 3 is a vertical sectional view taken on planes indicated by the broken dotted line 1-1 in Fig. 1 and looking in the direction of the arrow at said line.

35 Figure 4 is a top plan view showing the devices for varying the extent of line spacing movement.

40 Figure 5 is a vertical sectional view taken on planes indicated by the dotted line 2-2 in Fig. 4 and looking in the direction of the arrow at said line, a section of the end bar 45 of the platen carrier also being shown.

Figure 6 is a side elevation of the parts shown in Fig. 5 looked at from the left-hand side.

50 Figure 7 is a vertical sectional view taken on the plane indicated by the dotted line 3-3 in Fig. 1 and looking in the direction of the arrow at said line.

Figure 8 is a fragmentary top plan view showing the right-hand end portion of the platen and platen carrier with the line spacing mechanism associated therewith.

As appears from Figs. 1, 3 and 8, the traveling platen carrier or carriage consists in the present instance of a U-shaped platen frame comprising a rear plate or cross bar 55 1 from which project forwardly end bars or plates, the right-hand end bar only being shown in the drawing and numbered 2. A front strike rotatable cylindrical platen 3 is provided with bearing or axle portions 60 4, the right-hand axle 4 being shown with its associate twirler or knob 5. The platen axle bears on the end bars, the rotatable axis of the platen extending longitudinally of the platen frame or carrier and passing 65 centrally through the axle portions. The platen frame or carrier and platen are mounted to travel from side to side over the stationary frame of the machine, said carrier being mounted on roller bearings 70 6 which co-operate with suitable stationary guideways. Connected with the right-hand end of the platen 3 in any suitable manner, as for example by that employed in the No. 10 Remington typewriting machine, is a line 75 spacing wheel 7 which preferably is provided with ratchet teeth 8.

80 In order to hold the platen and prevent it from turning between line spacing operations detent devices are provided, as shown 85 in Figs. 1 and 3, comprising a roller detent 9 which is adapted to co-operate with the ratchet teeth 8 at the under side of the line spacing ratchet wheel 7. The roller detent 9 is arranged within the forked rear end 90 portion of an arm 10, said detent having a pivot pin 11 bearing in the forked portions of said arm 10. Said arm extends forward and somewhat downward and at its front end is provided with a hub portion 12 which 95 bears rotatably on a rod 13 extending longitudinally of the platen frame and supported in the end bars thereof, a boss 2^a projecting inward from the end bar 2, receiving the right-hand end portion of said rod 13. The hub 12 and the arm 10 are loosely confined between a cross pin 14 projecting from the rod 13 and the boss 2^a. Secured to the under side of the arm 10 by a screw 15 is a

leaf spring 16, the free rear end portion of which is adapted to bear against the lower portion of the cross bar 1. The construction is such that the spring 16 acting 5 through the arm 10 urges the roller detent 9 upward and maintains it yieldingly engaged with the ratchet teeth 8, said detent normally or between line spacing operations engaging with the line spacing wheel in the 10 space between two of the teeth 8 to hold the ratchet wheel and through it the platen 3 against accidental turning movements.

Adapted to co-operate with the line spacing wheel 7 at its rear upper side is a 15 pawl member or actuator 17 which is provided with a pawl tooth 18 and with a tail portion or nose 19. The pawl or toothed device 17 is pivotally connected at its lower end by a headed pivot pin 20 with the rear 20 end of an angularly shaped guide arm or link 21 which is arranged transversely of the platen and extends fore and aft of the machine, its forward end being recessed or countersunk to receive a headed shoulder 25 screw 22 which bears in a threaded opening in a boss 2^b projecting inward from the end bar 2 and provides a pivotal support for the arm 21. A spring friction washer 21^a surrounds the reduced portion of the boss 2^b 30 and is confined between a shoulder on said boss and the arm 21. Said arm is adapted to vibrate up and down in a vertical fore and aft plane about the pivotal center or shoulder screw 22, bearing during such pivotal movements on the head and shoulder portion of said screw, as will be understood from Fig. 3. This pivotal center 22 is eccentric of the platen axis, being forward of the platen axis and in substantially the 40 same horizontal plane. The pawl 17 is arranged at the left of the arm 21 and in the plane of the ratchet wheel 7 with which it co-operates. Actuating movements are communicated to the pawl by a lever 23 45 which is arranged below the arm 21 and is adapted to vibrate up and down in the same vertical fore and aft plane as does said arm, and hence is on the same side of the line spacing wheel as is the arm 21. Said 50 lever is of the third order, its rear end portion being slotted as indicated at 24 to co-operate with a pin 25 projecting laterally from the pawl 17 forward of its pivot, this pin and slot connection loosely connecting the lever 23 with the pawl 17. The forward end of the lever 23 is pivoted 55 on a headed shoulder screw 26 which is threaded into the end bar 2. The fulcrum or pivot 26 of the lever 23 is forward of the pivot 22 of the arm 21 and is substantially in the same horizontal plane with said pivot and with the platen axis, in respect to which the lever 23 is eccentrically mounted. The lever 23 receives line spacing impulses or 60 actuations from a device or link 27, the

lower end of which as will be understood from Figs. 1 and 7 is hooked through a hole in the lever 23 somewhat to the rear of the fulcrum 26. Said link 27 is angularly shaped, its upper end being hooked through 70 a hole in a crank arm 28 which is fixed by a screw 29 to the rear end of a member or rock shaft 30 and projects horizontally leftward therefrom. Said rock shaft 30 as appears clearly from Fig. 8 is arranged 75 fore and aft of the machine at right angles to the axis of the platen and takes bearing in a housing 31 which is preferably made integral with the right-hand end bar 2 and is bored out to receive the rock shaft and 80 its restoring spring 32 which is coiled around a reduced portion of the rock shaft within the housing, one end of said spring having a fixed anchorage and the other end being connected to the rock shaft. Forward 85 of the housing 31 the rock shaft is provided with a flange 33 which with the crank arm 28 cooperates with the housing or bearing 31 to prevent endwise displacement of the rock shaft. The forward or exposed portion 90 of the rock shaft extends forward and downward, terminating in a line spacing finger piece or handle 34 which is conveniently disposed with reference to the keyboard of the machine. The hand piece or handle 34 together with the downwardly curved portion 95 of the rock shaft constitute in effect a crank arm which together with the crank arm 28 and the bearing portion or body of the rock shaft provide a bell crank having an elongated pivot. This portion of the line spacing mechanism, that is the rock shaft 30 and the parts directly connected therewith comprising the two crank arms, is not 100 novel, corresponding substantially with parts found in the No. 10 Remington machine. The line spacing handle is adapted to be swung rightward in a substantially vertical plane parallel with the platen axis, causing the shaft 30 to rock and the crank 105 arm 28 to be swung downward to actuate the pawl controlling mechanism in a manner hereinafter described.

For varying the extent of line spacing movement, devices are provided comprising, 110 as will be understood from Figs. 1, 3-6 and 8, an arm or carrier 35 vertically arranged inside the end bar 2 and provided at its lower end with a laterally extending bearing pin 36 which bears in an opening indicated at 37 115 in said end bar, the arm 35 being thus pivotally supported at its lower end. Near its upper end the arm carries a leftwardly projecting stop pin or abutment 38 which serves as an arresting device or stop for the guide arm 21. The upper end portion of the arm 35 is formed with a cross head comprising a horizontal part 35^a extending rightward 120 over the top of the end bar and terminating in a downwardly projecting portion 35^b. 125

The cross head portion 35^a has mounted on it a spring pressed detent pin 39 of ordinary construction provided with a knurled button or finger piece 40 by which the detent pin may be raised against its spring 39^a. The cross head loosely embraces a plate 41 which is arranged on the top of the end bar 2 at its rear, the rear portion of said plate being provided with holes indicated at 42 which receive securing screws 43 that are threaded into the said end bar. The plate 41 curves upward and forward and is provided with a plurality of perforations or holes indicated at 44, there being three of such perforations in the present instance, the detent pin 39 being adapted for co-operation with these perforations to hold the pivoted stop carrier or arm 35 and the stop 38 in any one of three predetermined positions. At its outside edge the plate 41 is slotted or cut out as indicated at 45, providing end portions or stops 46. The downward extension 35^b of the cross head enters the cut-out 45 and is adapted to co-operate with the end stops 46 to limit back and forward swinging movements of the stop device 35. It will be understood that by pulling up the detent pin 39 by means of its finger piece 40 the stop device 35 may be released and swung on its pivot either forward or backward until the detent pin 39 is opposite the desired perforation 44, with which the detent pin may thereupon be caused to engage to locate the stop or abutment 38 in desired position.

This abutment determines the normal position of the arm 21 and through it that of the pawl 17. The arm 21 is maintained normally engaged with the abutment 38 by the action of the spring 32, the tension of which is transmitted to the arm 21 through the link 27 and the lever 23. In other words, the spring 32 is in effect a restoring spring for the entire train of line spacing mechanism beginning with the handle 34 and terminating with the pawl 17, and maintains these parts in the normal position illustrated in Fig. 1. From this figure it will be observed that the normal position of the arm 21 is determined by the stop 38 by which said arm is arrested. The normal position of the lever 23 is determined in turn by the arm 21 with the under side of which the rear end portion of said lever contacts. The position of the pawl 17 normally is determined by the arm 21 and the lever 23 with which said pawl is connected at separate points, these points being so located that normally the pawl tooth 18 is raised above and separated from the ratchet teeth 8 of the line spacing ratchet wheel. It will be understood that the normal position of the link 27 is in turn determined by the lever 23 with which the lower end of said link is connected, the link in its turn serving normally to position the rock shaft 30 and the parts fixed to it, including the handle 34. It will further be understood that the normal positions of the pawl 17 and the parts controlling it, including the arm 21 and lever 23, may be varied by varying the position of the stop or abutment 38 through manipulating the stop carrying arm 35, as has been described. In other words, when, as shown in the drawing, the stop carrier 35 is located in its foremost position and set therein by the interlocking engagement of the detent pin 39 with the foremost perforation 44, the arm 21 and the pawl 17 will be maintained swung forward to their foremost position, giving the pawl its greatest extent of line spacing movement, this movement in the present instance being sufficient to turn the ratchet wheel and platen through three units of line space distance. Similarly when the detent pin 39 is engaged with the middle perforation, the pawl is so located normally that its line spacing movement is restricted to two units of line space distance, while when the detent pin is engaged with the rearmost perforation 44 a single unit of line space distance will be communicated to the platen at each line spacing operation. Otherwise stated, the forward or illustrated location of the stop or abutment 38 positions the pawl for triple line spacing, the middle location positions it for double line spacing, and the rearmost for single line spacing.

The end of the line spacing movement is determined by stop devices which, as illustrated in Figs. 1 and 2, comprise a leaf spring or stop finger 47 which is secured to the upper face of the platen frame bar 1 in the vertical plane of the pawl 17. The lower end of the leaf spring 47 receives a headed screw 48 which is threaded into the bar 1 and secures the spring 47 thereto. The upper free end portion of said spring rests against an adjustable abutment in the form of a screw 49 which is threaded through the bar 1 and is held in adjusted position by a check nut 50. By adjusting this screw 49 up or down the free end or stop portion of the leaf spring 47 is raised or lowered to vary the position of arrest of the pawl 17 and its operating mechanism, the tail portion 19 of said pawl contacting with the leaf spring as shown in Fig. 2 to arrest the parts at the end of the line spacing movement. A stop pin 51 projecting laterally from the pawl 17 is adapted to contact with the top of the arm 21 when the platen is removed from the platen carrier, said pin preventing undue displacement of the pawl.

In operation the line spacing handle 34 is swung rightward rocking the shaft 30 and swinging the crank arm 28 downward, this movement being transmitted through the link 27 to the lever 23 which in turn will be swung downward about its fulcrum 26. This movement of the lever is transmitted

through the pin and slot connection 24, 25, to the pawl member 17 which during the initial stage of movement will turn on its pivotal center 20 independently of the arm 21, which arm will remain motionless until the pawl tooth 18 engages with the ratchet wheel 7. Thereafter, as the movement of the pawl 17 and its controlling mechanism is continued, such movement will be transmitted to the ratchet wheel 7 and the platen 3, which parts will be turned or rotated about the pivotal axis of the platen until the line spacing movement is ended, which occurs when the tail 19 of the pawl contacts with the stop 47. At the end of the line spacing movement as illustrated in Fig. 2, the pawl device 17 is so related to the line spacing ratchet wheel and the stop 47 that it is jammed into the ratchet wheel so as to prevent overthrow of the parts even when additional impetus results from the arrest of the carriage at the end of its return movement under the stroke or pull of the line spacing handle 34.

25 It will be observed that by my present invention there is provided a simple, efficient and novel line spacing mechanism comprising comparatively few parts, easily constructed and assembled and readily accessible for adjustment or other purposes.

Various changes may be made without departing from my invention.

What I claim is new and desire to secure by Letters Patent, is:—

35 1. In a typewriting machine, the combination of a platen carrier, a platen, a line spacing wheel connected to the platen, a rock shaft on said platen carrier, a lever connected thereto, an arm movable in the plane of said lever, and a pawl carried by said arm and directly connected with said lever, said pawl being operative by said lever to coat with said line spacing wheel.

2. In a typewriting machine, the combination of a platen carrier, a platen, a line spacing wheel connected thereto, a line spacing pawl, a lever connected to said pawl, a finger piece connected to said lever, a guide arm pivoted to swing in the plane of said lever, said pawl being pivotally connected to said arm, said pawl being movable to some extent by said lever independently of said arm and prior to coacting with said line spacing wheel.

55 3. In a typewriting machine, the combination of a platen carrier, a rotatable platen thereon, a line spacing wheel connected to said platen, a lever mounted to vibrate in a vertical plane transverse of the platen axis, a finger piece connected to said lever, a guide arm pivotally mounted to vibrate in a vertical plane transverse of said platen axis, a line spacing pawl normally separated from said wheel and connected directly both to said lever and to said arm, said lever being

operative to move said pawl independently of said arm into effective engagement with said line spacing wheel, said lever and said arm both thereafter moving with said pawl through the line spacing movement.

4. In a typewriting machine, the combination of a platen carrier, a platen, a line spacing wheel connected thereto, a line spacing pawl normally separated from said wheel, a guide arm pivoted eccentrically of said wheel and to which said pawl is pivotally connected, a lever having a direct loose connection with said pawl, and a finger piece connected to said lever, said lever being effective to move said pawl pivotally and independently of movement of said arm into engagement with said line spacing wheel, said lever and said arm both thereafter moving with said pawl to the completion of the line spacing operation.

5. In a typewriting machine, the combination of a platen carrier, a platen, a line spacing wheel connected to the platen, a rock shaft on said platen carrier, a lever operative in a plane transverse of said platen, an arm operative in a plane transverse of said platen, a pawl pivotally connected with said arm, connections between said rock shaft and said lever, and direct pin and slot connections between said pawl and said lever, said pawl coacting with said line spacing wheel.

6. In a typewriting machine, the combination of a platen carrier, a platen, a line spacing wheel connected to the platen, a line spacing pawl, an arm pivoted at one end forward of the platen axle and connected at its opposite end in rear of the platen axle to said pawl, a lever fulcrumed at one end and connected at its opposite end to said pawl, a finger piece, and connections between said lever and said finger piece.

7. In a typewriting machine, the combination of a platen carrier, a platen, a line spacing wheel connected to the platen, a rock shaft on said platen carrier, a line spacing pawl, an arm pivoted at one end forward of the platen axle and connected at its opposite end in rear of the platen axle to said pawl, a lever fulcrumed at one end and connected at its opposite end to said pawl, a link connected to said lever between its ends, and a crank arm fixed to said rock shaft and connected to said link.

8. In a typewriting machine, the combination of a platen carrier, a platen, a line spacing wheel connected to the platen, a rock shaft on said platen carrier, a line spacing pawl, an arm pivoted at one end forward of the platen axle and connected at its opposite end in rear of the platen axle to said pawl, a lever fulcrumed at one end and connected at its opposite end to said pawl, a link connected to said lever between its ends, a crank arm fixed to said rock shaft

and connected to said link, and a line spacing arm or handle fixed to said rock shaft.

9. In a typewriting machine, the combination of a platen carrier, a platen, a line spacing wheel connected to the platen, a line spacing handle on said platen carrier, a line spacing pawl operative on said wheel, an arm or link pivoted at one end to said platen frame and at its opposite end having a pivotal connection with said pawl, a lever pivoted at one end and having at its opposite end a pin and slot connection with said pawl, and connections between said lever and said handle.
10. In a typewriting machine, the combination of a platen carrier, a platen, a line spacing wheel connected to the platen, a line spacing pawl co-operative with said wheel, a line spacing finger piece, and connections between said finger piece and said pawl comprising a lever and an arm arranged one above the other and vibratable in the same plane, both said lever and said arm being directly connected to said pawl.
11. In a typewriting machine, the combination of a platen carrier, a platen, a line spacing wheel connected to the platen, a line spacing pawl operative on said wheel, a finger piece, a lever, connections between said finger piece and said lever, a pivoted guide arm to which said pawl is connected, and connections between said pawl and said lever, said lever and said guide arm being arranged at the same side of said line spacing wheel.
12. In a typewriting machine, the combination of a platen frame, a rotary platen mounted on said frame, a line spacing wheel connected to said platen, a line spacing pawl, a line spacing handle movable in a plane parallel with the platen axis, a pivoted arm movable in a vertical plane transverse of the platen axis to which said pawl is connected, a lever fulcrumed to vibrate in a vertical plane transverse of said platen axis and operative on said pawl, and connections between said handle and said lever, said lever and said arm both extending fore-and-aft transversely of the line spacing wheel, and being arranged at the same side of said wheel.
13. In a typewriting machine, the combination of a platen frame, a rotary platen mounted on said frame, a line spacing wheel connected to said platen, a line spacing pawl, a line spacing handle movable in a plane parallel with the platen axis, a pivoted arm movable in a plane transverse of the platen axis to which said pawl is connected, a lever fulcrumed to vibrate in a plane transverse of said platen axis and operative on said pawl, and connections between said handle and said lever, said connections comprising a rock shaft mounted to turn on said platen frame at right angles to the axis of
- the platen, said handle being fixed to said rock shaft, a crank arm fixed to said rock shaft, and a link connecting said crank arm and said lever, said lever and said arm both extending fore-and-aft transversely of the line spacing wheel, and being arranged at the same side of said wheel.
14. In a typewriting machine, the combination of a platen frame, a platen rotatably mounted thereon, a line spacing wheel connected to said platen, a line spacing actuator co-operative with said wheel, and means for operating said actuator, said means comprising a hand operated lever and a pivoted guide arm, said lever being fulcrumed eccentrically of the platen axis, and said guide arm being pivoted eccentrically of the platen axis, said lever and said guide arm both being vibratable transversely of said platen axis extending transversely of the line spacing wheel and on the same side thereof, said lever and said guide arm both being connected to said pawl independently of each other.
15. In a typewriting machine, the combination of a platen frame, a platen rotatably mounted thereon, a line spacing wheel connected to said platen, a line spacing actuator co-operative with said wheel, and means for operating said actuator, said means comprising a hand operated lever and a pivoted guide arm, both being vibratable up and down, said lever having its fulcrum forward of the platen axis and substantially in the same horizontal plane, and said guide arm being pivoted forward of said platen axis and substantially in the same horizontal plane, said pawl being connected directly both to said lever and to said guide arm.
16. In a typewriting machine, the combination of a platen frame, a cylindrical platen rotatably mounted thereon, a line spacing wheel connected to said platen, a line spacing pawl, a pivoted spring pressed guide arm operative in a vertical plane transverse of the platen axis and to which said pawl is pivotally connected, a stop for arresting said arm in normal position, and a hand operated lever of the third order vibratable in a vertical plane transverse of the platen axis and having a direct pin and slot connection with said pawl.
17. In a typewriting machine, the combination of a platen frame, a cylindrical platen rotatably mounted thereon, a line spacing wheel connected to said platen, a line spacing pawl, a pivoted spring pressed guide arm operative in a fore and aft plane transverse of the platen axis and to which said pawl is pivotally connected, a stop for arresting said arm in normal position, a lever pivoted at its forward end to vibrate in a plane transverse of the platen axis and having at its rear end a direct pin and slot connection with said pawl, a line spacing

handle, and operating connections between said handle and said lever comprising a device effective on said lever between its ends.

18. In a typewriting machine, the combination of a platen frame, a cylindrical platen rotatably mounted thereon, a line spacing wheel connected to said platen, a line spacing pawl, a guide arm operative in a fore and aft plane transverse of the platen axis and to which said pawl is pivotally connected, a stop for arresting said arm in normal position, a lever pivoted at its forward end to vibrate in a plane transverse of the platen axis and having at its rear end a direct pin and slot connection with said pawl, a link connected to said lever between its ends, a crank arm to which said link is connected, a rock shaft to which said crank arm is fixed, a line spacing handle at the forward end of said rock shaft, said handle being movable in a plane parallel with the platen axis, and spring means for restoring said rock shaft, lever and guide arm.

19. In a typewriting machine, the combination of a rotatable platen, a line spacing ratchet wheel connected thereto, a line spacing pawl, a guide arm pivotally supporting said pawl and itself pivoted eccentrically of the platen, a pawl operating lever engaged directly with said pawl below the guide arm and vibratable in the same plane, a stop for determining the normal position of the guide arm, said guide arm serving as a stop to determine the normal position of said lever, and spring means constantly tending to maintain said guide arm in contact with said stop and to maintain said lever in contact with said guide arm.

20. In a typewriting machine, the combination of a platen frame, a cylindrical platen rotatably mounted on said frame, a line spacing ratchet wheel connected to said platen, a line spacing pawl co-operating with said ratchet wheel, a guide arm pivoted at one end eccentrically of the platen and having at its other end a pivotal connection with said pawl, a stop, a pawl operating lever arranged below said guide arm and vibratable in the same plane, said lever having a pin and slot connection with said pawl, hand actuated means for operating said lever, and a spring effective on said lever to maintain it normally in contact with said guide arm, and said guide arm against said stop, said guide arm serving as a stop to determine the normal position of said lever.

21. In a typewriting machine, the combination of a platen frame, a front strike platen rotatably mounted thereon, a line spacing ratchet wheel connected to the platen, a line spacing pawl arranged behind said line spacing wheel, a fore and aft actuating lever loosely connected to said pawl, a fore and aft guide arm pivoted eccentrically of said platen and to which said pawl

is pivotally connected, a restoring spring operative on said guide arm, a stop for determining the normal position of said pawl, a hand operated lever for actuating said pawl, a roller detent co-operative with the ratchet wheel at its under side, a rod extending lengthwise of the platen and mounted on said platen frame, an arm pivoted on said rod and on which said roller detent is supported, and a spring effective on said pivoted arm.

22. In a typewriting machine, the combination of a platen frame, a cylindrical platen rotatably mounted thereon, a line spacing wheel connected to said platen, a line spacing pawl, a pivoted spring pressed guide arm operative in a fore and aft plane transverse of the platen axis and to which said pawl is pivotally connected, a stop for arresting said arm in normal position, a hand operated lever directly connected to said pawl, and a second stop fixed on said platen frame with which the tail of said pawl cooperates to arrest the parts at the end of the line spacing movement.

23. In a typewriting machine, the combination of a platen frame, a cylindrical platen rotatably mounted thereon, a line spacing wheel connected to said platen, a line spacing pawl, a pivoted spring pressed guide arm operative in a fore and aft plane transverse of the platen axis and to which said pawl is pivotally connected, a stop for arresting said arm in normal position, a hand operated lever connected to said pawl, and stop devices for determining the line spacing movement, said stop devices comprising a leaf spring secured at one end to said platen frame and an adjustable abutment cooperating with the free end of said leaf spring to vary its arresting position, said pawl coacting with the free end of said leaf spring.

24. In a typewriting machine, the combination of a platen frame, a platen rotatable thereon, a line spacing ratchet wheel connected to the platen, a line spacing pawl, mechanism for actuating said pawl, and stop devices for determining the normal position of said mechanism, said stop devices comprising a pivoted arm, a stop proper projecting laterally from said arm, a spring detent pin carried by said arm, and a plate provided with perforations and embraced by a bent portion of said arm.

25. In a typewriting machine, the combination of a platen frame comprising an end bar, a rotatable platen, a line spacing ratchet wheel connected to the platen, a line spacing pawl, mechanism for actuating said pawl, and stop devices for determining the normal position of said mechanism, said stop devices comprising a vertically arranged arm bent at its upper end portion to provide a cross head, the lower end of said arm being

provided with a pin pivotally engaging in an opening in said end bar, a stop lug proper projecting from said arm oppositely from said pin, a spring pressed detent pin mounted on said cross head, and a plate detachably secured to the top of said end bar and provided with a plurality of perforations with which said detent pin may co-operate.

26. In a typewriting machine, the combination of a platen frame comprising an end bar, a rotatable platen, a line spacing ratchet wheel connected to the platen, a line spacing pawl, mechanism for actuating said pawl, and stop devices for determining the normal position of said mechanism, said stop devices comprising a vertically arranged arm bent at its upper end portion to provide a cross head, the lower end of said arm being provided with a pin pivotally engaging in an opening in said end bar, a stop lug proper

projecting from said arm oppositely from said pin, a spring pressed detent pin mounted on said cross head, and a platen detachably secured to the top of said end bar and provided with a plurality of perforations 25 with which said detent pin may co-operate, said plate being embraced by said cross head, said cross head comprising a downwardly projecting portion co-operating with a slot in said plate to limit pivotal movements of 30 said arm.

Signed at the borough of Manhattan, city of New York, in the county of New York and State of New York this 25th day of January, A. D. 1921.

JOHN H. BARR.
